TRUNK LOCKER

Raymond A. Baustian and Emile A. Barth, York, Pa., Hugh E. Burke, Hempstead, N. Y., and Benjamin F. Hantz, York, Pa., assignors to the United States of America as represented by the Secretary of the Army

Application July 24, 1952, Serial No. 20,747

Term of patent 3½ years

(Cl. D87—5)

To all whom it may concern:

Be it known that we, Raymond A. Baustian, Emile A. Barth, Hugh E. Burke, and Benjamin F. Hantz, citizens of the United States, residing at York, in the county of York and State of Pennsylvania, at York, in the county of York and State of Pennsylvania, at Hempstead, in the county of Nassau and State of New York, and at York, county of York and State of Pennsylvania, respectively, have invented a new, original, and ornamental Design for a Trunk Locker, of which the following is a specification, reference being had to the accompanying drawings, forming a part thereof.

Figure 1 is a perspective view of our ornamental design for a trunk locker;

Figure 2 is a plan view thereof;

Figure 3 is a bottom plan view thereof;

Figure 4 is a rear elevational view thereof; and

Figure 5 is an end elevational view of the same.

The broken line showing of the handle and lock portions in Figure 1 is for the purpose of illustration only.

We claim:

The ornamental design for a trunk locker, substantially as shown and described.

RAYMOND A. BAUSTIAN.
EMILE A. BARTH.
HUGH E. BURKE.
BENJAMIN F. HANTZ.
